UNITED STATES PATENT OFFICE.

CHARLES HARDY, OF NEW YORK, N. Y., ASSIGNOR TO AMSCO PRODUCTS, INC., OF NEW YORK, N. Y., A CORPORATION OF NEW YORK.

ELECTRON-DISCHARGE-TUBE SOCKET.

Application filed October 12, 1925. Serial No. 61,931.

This invention relates to improvements in sockets or receptacles for electron discharge or vacuum tubes of the type employed in radio receiving sets.

5 The principal object of my present invention comprehends the provision of an improved socket for electron discharge or vacuum tubes embodying a construction which is designed to meet various requirements of service of the manufacturer, assembler and user of radio receiving sets in a highly efficient and economical manner.

More specifically, the prime desiderata of the present invention include the provision 15 of an electron discharge tube socket constructed and designed so as to be capable of being manufactured in large quantities economically and uniformly, assembled in radio receiving sets with facility and rapidity and 20 used with convenience and efficiency, the still further provision of a vacuum tube socket constructed to form a substantially closed casing or receptacle, housing or enclosing the resilient contact elements thereof, the 25 socket being adapted to receive the electron discharge tube in only one position, with the contact pins of the tube cooperating in a predetermined way with the contact elements of the socket; the further provision of an 30 improved socket of this type in which the resilient contact elements of the socket engage the sides of the tube contact pins to produce a clean and effective electrical engagement or contact therewith, and to hold 35 the tube securely in its mounted position; the still further provision of an improved socket of the nature referred to which is readily mountable, as by means of a single securing element, on a base or sub-base of a 40 radio receiving set; the further provision of a socket structure defining a substantially closed casing made of body and cover sections which may be readily assembled to produce the casing unit, and in which the 45 parts are coordinated to interengage or interlock, so that the socket may be manufactured with a minimum of parts correlated to produce a rugged and strong structure; and the further provision of an electron discharge tube socket having its parts coordinated to produce a neat and attractive 50 appearance and design.

To the accomplishment of the foregoing and such other objects as will hereinafter appear, my invention consists in the ele-

ments and their relation one to the other, as hereinafter more particularly described and sought to be defined in the claims; reference being had to the accompanying drawing which shows the preferred embodiment of 60 my invention, and in which:

Fig. 1 is a cross-sectional elevational view of a socket embodying the principles of my invention and showing the manner of its use,

65 Fig. 2 is a view of the same taken in cross-section in the plane of the line 2—2, Fig. 1,

Fig. 3 is a view of the same taken in cross-section in the plane of the line 3—3, Fig. 1, and

70 Fig. 4 is a top plan view thereof.

Referring now more in detail to the drawings, the electron discharge tube socket of my present invention comprises a body section generally designated as A and a cover section generally designated as B united together to form a substantially closed casting or receptacle housing or enclosing the contact elements of the socket, the cover section B defining a base for receiving and 75 mounting the electron discharge tube generally designated as C.

The base or cover section B of the socket comprises a unitary member made of an insulation material molded to provide the cover portion 10 and the integral hub portion 11, the said hub portion defining a means for receiving a securing element such as a screw 12 for attaching the socket structure to a support such as a mounting 80 base 13, the said hub 11 being provided with a metallic insert 14 molded in the hub 11, which insert defines a rivet or securing means for uniting the base B to the body A of the socket, as will become clearer here- 85 inafter

The base or cover section B is designed to receive in a predetermined position the contact pins of the tube C, the said base being provided with a plurality of orifices 15, 16, 17 and 18, which are dimensioned and relatively spaced to receive the contact pins 19, 20, 21 and 22 of the vacuum tube C. From a consideration of Figs. 1, 2 and 3 of the drawings, it will be seen that 100 the width of the orifices 17 and 18 is greater than that of the orifices 15 and 16, and that these orifices are spaced non-uniformly about the axis of the socket to correspond to the dimensions and spacing of the con- 105 110

tact pins 21 and 22 and 19 and 20, so that the vacuum tube is receivable by the socket in only a given or predetermined position, so as to obviate improper mounting of the tube on the socket.

For cooperation with the contact pins 19-22 of the electron discharge tube C, there is provided a plurality of resilient contact elements 23, 24, 25 and 26 which are secured interiorly to the base or cover section B, each of the contact elements being secured to the cover section preferably by means of a rivet 27, each of the said contact elements being disposed radially of the socket base, so that its outer end extends radially from the socket structure for ready connection or attachment to the electrical wiring of the radio receiving set, the inner end of each contact element being disposed adjacent and below one of the contact pin receiving orifices and in the path of movement of a tube contact pin so as to engage the side of a contact pin when the tube is mounted on the socket base. Preferably the construction is such that the contact pins and contact elements engage with a scraping action so as to remove the oxidized surface on either contact element, and thus produce efficient electrical engagement. To accomplish this object, the inner ends 23'-26' of the contact elements are bent so that the outer free edges thereof are positioned in the path of movement of the contact pins 19-22 to engage the latter with a scraping action.

It will be noted that each of the contact elements is attached to the cover section or base B at only one point by means of the rivets 27, and in order to retainingly seat the contact elements or springs 23-26 against rotation, the base B is preferably formed with pairs of integral ribs 28 and 29, one pair for each contact element, the ribs of a pair defining a seat for receiving the contact element or spring and retaining the same against rotation about the securing rivet, as will be clearly apparent from a consideration of Figs. 1 and 3 of the drawings. Preferably the base or cover section B is provided with an integral raised annulus 30 for seating the base of the vacuum tube C.

The socket body A in the preferred construction comprises a cup-shaped element also made of an insulation material molded to provide a bottom wall 31 and a side wall 32, the said bottom wall being provided with a central aperture 33 which receives the metallic insert or rivet 14 of the cover section, the lower edge of said rivet being flanged over or riveted onto the underneath wall of the body bottom 31 to unite the body and cover sections together to form the socket unit, as will be clearly apparent from a consideration of Fig. 1 of the drawings.

With this construction, it will be seen that

the socket unit may be attached or mounted on a support such as a base board 13 with the use of a single securing element such as 12, the bottom of the cup A being provided with a plurality of integral prongs 34 which, when pressed into the base board 13, retain the socket unit against rotation thereon. Preferably the hub 11 of the socket is provided at its top with a countersunk portion 35 for receiving and concealing the head of the securing screw 12. The cup A may further be provided with the integral strengthening ribs 36, 36.

To prevent displacement or rotation of the cover section B on the cup or body section A, the top of the body side wall 32 is provided with a plurality of cut-out portions 37, 38, 39 and 40 (see particularly Figs. 1 and 4 of the drawings) which accommodate and receive the extending or protruding ends of the leaf contact elements 23-26 and cooperate therewith to prevent rotation of the casing section B on the body casing section A.

The manner of making, assembling and using the improved socket of my invention and the many advantages thereof will in the main be fully apparent from the above detailed description thereof. It will be apparent that the body and cover sections A and B of the socket define a substantially closed casing or receptacle which houses or encloses the contact elements and pins of the socket and vacuum tube, with the cover of the casing forming a tube receiving base 100 which receives the vacuum tube in only one predetermined position, thus inhibiting a mismounting of the tube on the socket. It will be further seen that the contact elements of the socket are designed so as to assure a clean contact with the contact pins of the tube by producing a scraping and cleaning action therebetween, the engagement of the socket contact elements producing, moreover, a lateral thrust on the contact pins of the vacuum tube which assists in holding the tube in position on the socket base. From a manufacturing viewpoint, it will be seen that the cup and cover sections may be readily molded in attractive designs, 115 and may be rapidly assembled by first attaching the contact elements 23-26 onto the cover section B and by riveting the hub of the cover section centrally to the cup section A, the parts interlocking to produce a strong socket unit. It will be further apparent that the socket units may be readily assembled in quantities, the same requiring the employment of only a single securing screw. The parts, moreover, 120 cooperate to produce a neat and attractive appearance and design.

While I have shown and described my invention in the preferred form, it will be apparent that numerous changes and modifi- 130

cations may be made in the structure disclosed without departing from the spirit of the invention, defined in the following claims.

5. I claim:

1. An electron discharge tube socket comprising body and cover sections, one of said sections being provided with an orificed hub secured to the other section for uniting the sections together to form a substantially closed casing, the hub defining a means for receiving a socket securing screw or the like, one of said sections defining the tube receiving base and being provided with a plurality of orifices dimensioned and relatively spaced to receive the contact pins of the tube, and resilient contact elements secured interiorly to one of the casing sections and positioned to be engaged by the contact pins when the tube is placed on the socket base.
2. An electron discharge tube socket comprising body and cover sections, one of said sections being provided with an orificed hub secured to the other section for uniting the sections together to form a substantially closed casing, the hub defining a means for receiving a socket securing screw or the like, one of said sections defining the tube receiving base and being provided with a plurality of orifices dimensioned and relatively spaced to receive the contact pins of the tube, and resilient contact elements secured interiorly to one of the casing sections, each having its end edge positioned below one of said orifices in the path of movement of a tube contact pin so as to be arranged to engage the side of a contact pin with a scraping action when the tube is mounted on the socket base.
3. An electron discharge tube socket comprising body and cover sections, one of said sections being provided with an orificed hub secured to the other section for uniting the sections together to form a substantially closed casing, the hub defining a means for receiving a socket securing screw or the like, the said cover section defining the tube receiving base and being provided with a plurality of orifices dimensioned and relatively spaced to receive the contact pins of the tube, and leaf contact springs secured interiorly to said base having inner ends adapted for engaging the tube contact pins and having outer ends extending laterally from the socket casing, the top of said casing body being provided with cut-out portions for accommodating and receiving the extending ends of the contact springs and cooperating therewith to prevent rotation of the cover casing section on the body casing section.
4. An electron discharge tube socket comprising body and cover sections, one of said sections being provided with a screw receiving hub portion secured to the other section

for uniting the sections together to form a substantially closed casing, the said cover section defining the tube receiving base and being provided with a plurality of orifices dimensioned and relatively spaced to receive the contact pins of the tube, contact springs for cooperation with the contact pins each secured interiorly at one point to said base, the base being formed with integral means for seating the springs against rotation, the said springs having outer ends extending radially from the socket casing and the top of said casing body having cut-out portions for accommodating and receiving the extending ends of the springs and cooperating therewith to prevent rotation of the cover casing section on the body casing section.

5. An electron discharge tube socket comprising a cup section, a cover section forming a tube receiving base, both sections made of molded insulation material, one of said sections having an integral hub portion provided with a rivet insert which is riveted to the other section, a plurality of orifices in the cover section, contact springs riveted interiorly to the cover section each having an inner end adjacent an orifice and an outer end extending radially from the socket, the cover section being ribbed to provide retaining seats for the springs.

6. An electron discharge tube socket comprising a cup section, a cover section forming a tube receiving base, both sections made of molded insulation material, one of said sections having an integral hub portion provided with a rivet insert which is riveted to the other section, a plurality of orifices in the cover section, contact springs riveted interiorly to the cover section each having an inner end adjacent an orifice and an outer end extending radially from the socket, the cover section being ribbed to provide retaining seats for the springs, the top of said cup section having cut-out portions accommodating and receiving the extending ends of the springs and cooperating therewith to prevent rotation of the cover section on the cup section.

7. An electron discharge tube socket comprising body and cover sections forming a substantially closed casing, one of said sections having an integral central hub portion provided with a rivet insert which is riveted to the other section, one of said sections defining the tube receiving base being provided with a plurality of orifices dimensioned and relatively spaced to receive the contact pins of the tube, and resilient contact elements secured interiorly to one of the casing sections and positioned to be engaged by the contact pins when the tube is placed on the socket base.

8. An electron discharge tube socket comprising body and cover sections forming a

substantially closed casing, one of said sections having an integral central hub portion provided with a rivet insert which is riveted to the other section, one of said sections defining the tube receiving base being provided with a plurality of orifices dimensioned and relatively spaced to receive the contact pins of the tube, and a plurality of

contact means riveted interiorly to one of said sections, each contact means having an inner end adjacent an orifice and an outer end extending from the socket casing.

Signed at New York city, in the county of New York and State of New York, this 8th day of October A. D. 1925.

CHARLES HARDY.
